CLAIM

The ornamental design for a tool for applying pressure to parts of the human back and neck, as shown and described.

DESCRIPTION

FIG. 1 is a side elevational view of a tool for applying pressure to parts of the human back and neck showing our new design, the opposite side being a mirror image thereof;

FIG. 2 is a side elevational view thereof looking from the left in FIG. 1;

FIG. 3 is a side elevational view thereof looking from the right in FIG. 1;

FIG. 4 is a top plan view thereof; and,

FIG. 5 is a bottom plan view thereof.

FIG. 4

FIG. 2

FIG. 1

FIG. 3

FIG. 5
